UNITED STATES PATENT OFFICE.

DAVID WILEY McCaughey, OF CHICAGO, ILLINOIS.

DIRIGIBLE TORPEDO.

SPECIFICATION forming part of Letters Patent No. 767,490, dated August 16, 1904.

Application filed March 20, 1902. Serial No. 99,115. (No model.)

To all whom it may concern:

Be it known, that I, DAVID WILEY McCaughey, a citizen of the United States, residing at Chicago, in the county of Cook and State of Illinois, have invented certain new and useful Improvements in Dirigible Torpedoes, of which the following is a specification.

This invention relates to that class of torpedoes which is provided with self-contained mechanism by which the movements thereof may be controlled, and particularly to that class of torpedoes which is arranged to be controlled—that is, moved through the water in any desired direction—by electrically-actuated mechanisms, all of which will more fully hereinafter appear.

The principal object of the invention is to provide a simple, economical, and efficient electrically-controlled torpedo.

20 A further object of the invention is to provide a torpedo with electrically-actuated mechanisms connected with the shore-line with but a single insulated wire and arranged and constructed in such a manner as to be operated, directed, and controlled from the shore by means of the electric current passing through said wire.

The invention consists, further and finally, in the features, combinations, and details of construction hereinafter described and claimed.

In the accompanying drawings, Figure 1 is a diagrammatic view showing my improved controlling devices as they appear when used in connection with the torpedo. Fig. 2 is a plan 35 sectional view of one form of torpedo as it appears when constructed in accordance with these improvements. Fig. 3 is a side elevation, partly in section, of the same; and Fig. 4 is an enlarged sectional detail of the upper part of 40 spool-holding rod shown in the lower part of Fig. 3, as will be more fully hereinafter explained. Fig. 5 is a diagrammatic illustration of the reversible motor which is used to turn the rudder.

45 In the art to which this invention relates it is well known that it is highly desirable to provide a means by which an explosive torpedo may be launched from the shore or from a vessel and directed toward a given mark and

exploded by contact therewith or at any desired point adjacent thereto. To accomplish this result, various devices and expedients have been used, some of which give more or less satisfaction and all of which contain objections which render their use somewhat undesirable. 50 This invention, therefore, is designed principally to overcome as many objections of the prior art as possible and provide a simple, economical, and efficient torpedo, which may be controlled from the shore by the use of a 55 single conducting-line which conveys currents of various intensities to the mechanism and is arranged to operate the desired mechanism, and thereby direct and control the movements of the torpedo, as will be hereinafter more fully 60 explained.

In Fig. 1, A is an electric motor, the armature of which is attached directly to the shaft 8 of the propeller. (See Figs. 2 and 3.) B is an electric motor whose armature is attached 70 to the shaft 2, (see Fig. 2,) upon which there is a worm which operates in a worm-wheel 3, Fig. 2, thereby operating shaft 4 and worm 5. Worm 5 works in worm-wheel 6, Fig. 2, which is attached to rudder-post 7. 75

Electric motor B is constructed in such a manner that the direction of the motion of its armature depends upon the direction of the current—that is to say, if a direct current will cause its armature to revolve from left to 80 right then an inverse current will cause its armature to revolve from right to left. Electric motor A is constructed in such a manner that its armature will revolve in the same direction no matter whether a direct or inverse 85 current is used. It is apparent, therefore, that when an electric current passes through the motor A the propeller 1 will always rotate in the same direction—that is, so as to propel the torpedo forward. It is also apparent that the rudder 85, Fig. 3, will swing either to the right or the left, its motion depending upon the direction of the current which passes through motor B.

I will now describe the mechanism by means 90 of which the motor B, which controls the working of the rudder, can be cut into or out of the circuit at the will of the operator, the opera-

tor thus being enabled to control the direction of the torpedo without interfering in any manner with its forward motion.

In Fig. 1, C is an automatically-operated switch, which, with the motors A and B, is located in the torpedo. This switch C is composed of a number of segments which are alternately conductors and non-conductors and which are arranged, as shown in the diagram, in two concentric circles. The conducting-segments of the outer circle are 9, 10, 11, and 12. The conducting-segments of the inner circle are 13, 14, 15, and 16. The switch has the conducting-arm and brush 17 extending from a pivot 18 at its center and which connects successively with the segments above enumerated and which is operated by a ratchet 81, which is moved in a step-by-step manner by means of an armature-lever 19, which is arranged in such a manner as to be operated by the magnet D when D is energized. Around the outer edge of the switch C are two concentric conductors 20 and 21. 20 has metallic connection with the outer conducting-segments 9, 10, 11, and 12 through wires 22, 23, 24, and 25, respectively. Conductor 21 has metallic connection, as shown in the diagram, with the conducting-segments of the inner circle 13, 14, 15, and 16, respectively, through the wires 26, 27, 28, and 29, respectively. The conducting-segments of the outer circle are constructed in such a manner that no radius drawn from the center of pivot 18 to any part of any of said conducting-segments 9, 10, 11, and 12 can pass through or touch any part of said segments 13, 14, 15, or 16, and no radius drawn from the center of said pivot 18 to any part of said conducting-segments 13, 14, 15, and 16 can pass through any part of said segments 9, 10, 11, and 12.

E is an indicator located on the shore and used solely to enable the operator to know the position of the switch-arm or brush 17. Ratchet 30 corresponds with ratchet 81 of the switch above described. Ratchet 30 is operated by armature-lever 80, which is arranged adjacent to and operated by magnet F. Arm 32 corresponds to arm 17 of the switch, and the relative positions of 32 and 17 are always the same. The segments of the indicator correspond with the segments of the switch, the segments 33, 35, 37, and 39 corresponding with the segments 13, 14, 15, and 16 of the switch and the segments 34, 36, 38, and 40 of the indicator corresponding with segments 10, 11, 12, and 9 of the switch.

G is a source of electrical power, either a battery or a dynamo, located on shore.

H is a key for making and breaking the circuit.

I is a switch for reversing the current.

E, F, G, H, and I are located on the shore.

A, B, C, and D are located in the torpedo.

I will now describe the method of operating 65 the above mechanism.

The current starts from the battery G, passes through wire 4 to magnet F, energizing it, thence through wire 42 to switch-arm 43, thence to button 44, thence through wire 45 to magnet D, which it energizes, thence to wire 46 to the pivot 18, thence through switch-arm and brush 17 to switch-segment 13, thence through wire 26 to conductor 21, thence through wire 47 to motor B, thence through wire 48 to motor A, thence through wire 49 to the water at 50, and thence through the water and land to 51, thence by wire 52 to button 53, thence by arm 54 and wire 55 to key H, thence through wire 56 back to the battery.

When the current flows in the direction as above described, the motors A and B are both operated. Motor A will propel the torpedo forward, while motor B will move the rudder 8. (See Figs. 2 and 3.)

The motor B is constructed in such a manner that if a direct current will cause its armature to revolve from the left to right an inverse current will cause its armature to revolve from right to left. The operator is thus enabled by means of the switch I to use either a direct or an inverse current, and thereby turn the rudder either to the left or to the right, as desired.

I choose to call the current above described a "direct" current, and in this description we will suppose that the direct current affects the motor in such a manner as to turn its armature in such a direction that the rudder 8 is turned to the left and the inverse current will act to turn the rudder 8 to the right. Let us suppose that the mechanism remains exactly in the position shown in Fig. 1, except switch I, which we will suppose to be in such position that its arm 54 is in contact with button 57 of the switch and the arm 43 is in contact with button 53 of the switch. The current will then flow through the motors A and B in an opposite direction—that is to say, the current will leave the battery G by wire 4, pass through magnet F, wire 42, arm 43, button 53, wire 52 to the ground at 51, thence through the ground and water to 50, thence through wire 49, motor A, wire 48, motor B, wire 47, conductor 21, wire 26, segment 13, switch-brush and arm 17, wire 46, magnet D, wire 45, wire 58 to button 57, thence through arm 54 and wire 55, key H and wire 56 back to the battery. This current last described I choose to call an "inverse" current.

The mechanism is arranged in such a manner that when the current is passing through the circuit, as represented in Fig. 1, the magnets D and F are energized, and the corresponding armature-levers 19 and 80 are attracted to them, as represented in Fig. 1. When, however, the current is broken, the magnets D and F are deenergized, and the springs 59 and 58 draw the corresponding armature-levers 19 and 80 away from D and E, 130

respectively. In consequence of armature-levers 19 and 80 turning upon their respective pivots 82 and 83 the ratchets 81 and 30 are operated in a step-by-step manner by making 5 and breaking the circuit.

Now suppose the mechanism is in the same position as represented in Fig. 1 and the operator has moved the rudder to the desired position and desires to cut the motor B out 10 of the circuit, so that the torpedo may still be propelled forward without changing its direction. In order to do this, the current is broken for an instant by pressing down the key H. The armature-levers 19 and 80 being 15 no longer attracted by the magnets D and F will be drawn down to their normal positions against stop-pins 60 and 70. As soon as the current is allowed to flow, however, by removing the pressure from the key H the 20 magnets D and F are again energized and attract their respective armatures, and thereby operating the ratchets 81 and 30 in such a manner as to throw the arms 17 and 32 around into contact, respectively, with segments 9 25 and 40. Supposing the switch I to be in the position as shown in Fig. 1 and the switch-lever 17 to be in contact with segment 9, the current will then flow from the battery G through wire 4, magnet F, wire 42, arm 43, 30 button 44, wire 45, magnet D, wire 46, switch-arm 17 to segment 9 of the switch, thence by wire 22 to conductor 20, thence through wire 71 and wire 48 to motor A, thence through wire 49 to the water at 50, thence through 35 water and land to 51, thence through wire 52, button 53, arm 54, wire 55, key H, and wire 56 back to the battery. It will therefore be seen that when the switch-lever 17 is in contact with segments 9, 10, 11, or 12 of the 40 switch the current will flow through the motor A, but will not flow through the motor B, and it will also be seen that when switch-arm 17 is in contact with segments 13, 14, 15, and 16 of the switch the current will flow through 45 both of the motors A and B. Inasmuch as the position of the arm 32 always corresponds with the position of the switch-lever 17, the operator is enabled at all times to tell whether one or both of the motors are in operation 50 and which direction the rudder is being turned. By use of the switch I and key H the operator is enabled to use at will either motor A alone or motors A and B together and either a direct or inverse current, and is thereby 55 enabled to turn the torpedo either to right or left without interfering with its forward motion.

In order that the flow of current may not be interrupted while the switch-brush 17 is 60 passing from one segment of the switch to another, the switch-brush 17 is made so broad that in passing from one segment to another—(for instance, from segment 13 to segment 22) there will be an instant of time when it will 65 be in contact with two segments, during

which time the current will always pass through both motors A and B. The switch-brush is made so narrow, however, that when it is at rest, as represented in the drawings, Fig. 1, it will never be in contact with more 70 than one conducting-segment, so that the switch-brush can be brought to rest in such a position as to cause the current to pass through either one or both of the motors at the will of the operator. 75

To provide means for holding the electric conducting-wire, which may be taken as wire 45 of the drawings, I prefer to put the spool K, containing the same, in the torpedo, as shown in Fig. 3. Near the end of the wire, 80 as at 71, Fig. 4, said spool is connected, by means of a button 72, with the brush 73, and from thence the current passes to the motors, so that as the torpedo is moved out there will be little or no drag of wire. The spool K 85 is worked either upon a pointed pivot or ball-bearings, so as to cause as little friction as possible and should be inclosed in a funnel-like apartment 84, Figs. 2 and 3, with an opening at 74 sufficient to allow the wire 45 to 90 pass, which opening should be well back toward the stern of the torpedo in order to facilitate the unwinding of the spool K. It should be understood, however, that the spool may be placed on the land and the wire be 95 paid out automatically as the torpedo is directed or controlled.

Reversible motors are well known in common use. In Fig. 5, however, I have illustrated diagrammatically a reversible motor 100 mechanism, including a switch 130, such as I employ and which may be said to constitute a portion of such motor mechanism.

I will now describe the manner of reversing the motion of the armature of the motor 105 B. (See Fig. 1.)

In Fig. 5, B is a diagrammatic illustration of motor B, as described in connection with Fig. 1, and which is used to turn the rudder in the desired direction, as hereinbefore described. 110

In Fig. 5, 100 is a soft-iron wire-wound magnet, and 101 is a permanently-magnetized portion of a pivoted armature-bar 102, energized and placed adjacent to such magnet in 115 such a manner that the pole nearest the magnet will be attracted thereby whenever the magnet is energized by a direct current.

When the parts are in the position shown in Fig. 5, with electric current flowing from 120 battery G through wire 47, (see Fig. 1,) thence around magnet 100, energizing same, armature 101 will be attracted and drawn down into contact with magnet 100, as shown in Fig. 5. The current will then flow from 125 magnet 100 through wire 104; thence through pivoted armature-bar 102 to contact-post 105 and through the same; thence through contact-spring 106; thence through wire 107 and around field-magnet 108, energizing it; thence 130

through wire 109 and around field-magnet 110, energizing same; thence through wire 111, contact-spring 112, post 113, post 114, spring 115, wire 116 to and around armature-magnets 117, energizing same; thence through wire 48 to motor A, and thence through wire 49 and back to battery G, as hereinbefore described.

The armature and field magnets of motor B are wound in such a manner as to cause armature-magnets 117 to revolve in a given direction—that is, in such a direction as to cause the rudder to turn from right to left when said motor B is operated by a direct current. Now if it is desired to turn said rudder from left to right the operator turns the reversing-switch I, (see Fig. 1,) so that arm 54 comes into contact with button 57. (See Fig. 1.) The current will now flow through wire 47 in an opposite direction to that last described, and hence will flow around magnet 100 in such a direction as to cause it to repel armature-bar 101 until armature-bar 102 impinges against pin 127, in which position posts 118, 123, and 124 will be in contact with springs 119, 122, and 125, respectively, and contact between posts 105, 113, and 114 and springs 106, 112, 115, respectively, will be broken. The current will now flow from battery through wire 48, Figs. 1 and 5, thence around armature-magnets 117, energizing same, thence through wire 116, wire 126, spring 125, metallically-connected posts 124 and 123, spring 122, wire 121, wire 107, thence around field-magnet 108, energizing same, thence through wire 109, thence around magnet 110, energizing same, thence through wire 111 and 120 to spring 119, thence through post 118, bar 122, wire 104, around magnet 100, energizing same, as hereinbefore described, thence through wire 47 and back to the battery G in manner hereinbefore described.

It will be seen that the inverse current passes around the armature 117 in an opposite direction to the direct current, the result being that the respective poles of the armature-magnets 117 will be reversed with reversal of current. It is also apparent that the direct current and inverse currents will flow around field-magnets 108 and 110 in the same direction, and that therefore the polarity of the field-magnets will remain the same, no matter whether a direct or inverse current be used, the result being that the direction of the motion of the armature 117 will be reversed when the direction of the actuation-current is reversed, as hereinbefore suggested. Posts 105 and 118, Fig. 5, are so adjusted with reference to springs 106 and 119, respectively, that while magnet 101 is moving between magnet 100 and pin 127, as hereinbefore described, there is an instant of time when each of said posts is in contact with its respective spring, and in like manner there is an instant of time when posts 113 and 114 are in contact

with springs 112 and 115, respectively, and posts 123 and 124 will respectively also be in contact with springs 122 and 125. These periods of double contact, however, last but for an instant, for when movable armature-bar 102 comes to rest, either by impinging upon pin 127 or by magnet 101 impinging against magnet 100, there will be a contact between the respective posts and springs on one side only of movable bar 102. Posts 113 and 114 and posts 123 and 124 are respectively insulated from bar 102.

In Fig. 5 I have illustrated a reversible motor B, (shown in Fig. 1,) including the switch mechanism by means of which the direction of rotation of such motor is reversed, and which switch mechanism may therefore be said to be an essential part of an ordinary reversible motor mechanism. It will be understood, of course, that this or any ordinary and well-known form of reversible motor and switch mechanism may be employed.

The motor A is the ordinary type of electric motors, and no switch mechanism, such as 130, is used in connection therewith. Therefore the armature of motors A will always rotate in the same direction, no matter whether a direct or inverse current is used, because the actuating current flowing around its field and armature magnets will always be correspondingly and simultaneously reversed, the resultant effect being the same as though neither had been reversed.

I claim—

1. In a torpedo of the class described, the combination of a plurality of electric motors for operating a movable part or parts, a single line-wire connecting the same with the shore, a step-by-step switch in such line-wire, and electromagnetic mechanism for operating such switch to supply current to one or both of such motors, substantially as described.

2. In a torpedo of the class described, the combination of propelling and rudder mechanism, electric motors for operating the same, a single line-wire connecting the same with the land and with a source of electric energy, a step-by-step switch interposed between the motors and the source of electric energy, and electromagnetic mechanism for operating such switch to supply current to one or both of such motors, substantially as described.

3. In a torpedo of the class described, the combination of propelling and rudder mechanism, a motor connected with the propelling mechanism, a motor connected with the rudder mechanism, a step-by-step switch connected with both such motors, a single line-wire connecting such switch with the shore and with a source of electric current, and electromagnetic mechanism for operating such switch to supply current to one or both of such motors, substantially as described.

4. In a torpedo of the class described, the combination of propelling mechanism, rudder

- mechanism, a motor connected with the propelling mechanism, a motor connected with the rudder mechanism, an electric conducting-wire connecting both of such motors together, 5 a step-by-step switch electrically connected with such motors in series and between the same, a single line-wire connecting such switch with the shore and with the source of electric current, and means for operating such switch 10 to make and break the electric circuit and supply current to one or both of such motors, substantially as described.
5. In a torpedo of the class described, the combination of propelling mechanism, rudder mechanism, an electric motor connected with the propelling mechanism, an electric motor connected with the rudder mechanism, an electric conducting-wire connecting both of such motors together, a step-by-step switch connected with such motors in series and with the propeller-motor alone, a single line-wire connecting such step-by-step switch with the shore and with a source of electric current, and electromagnetic mechanisms for operating the 15 step-by-step switch to make and break the circuit so as to supply current to both of such motors or to the propeller-motor alone, substantially as described.
6. In a torpedo of the class described, the combination of propelling mechanism, rudder mechanism, an electric motor connected with the propelling mechanism, an electric motor connected with the rudder mechanism, electric conducting-wires connecting both of such 20 motors together, step-by-step switch electrically connected with both of such motors, electromagnetic mechanism for operating the step-by-step switch, a single line-wire electrically connecting the step-by-step switch with the shore and with a source of current-supply, and a key for making and breaking such circuit to energize and deenergize the electromagnetic mechanism and cause the operation of the step-by-step switch, substantially as described.
7. In a torpedo of the class described, the combination of propelling mechanism, rudder mechanism, an electromotor for such propelling mechanism, an electric motor for such 25 rudder mechanism, a step-by-step switch electrically connected with both of such motors in series and with the propelling-motor alone, electromagnetic mechanism for operating such step-by-step switch, a single line-wire connecting such electromagnetic mechanisms with the shore and with a source of electric current, a key for making and breaking such main line to energize and deenergize the magnets and cause the operation of the parts, and a dummy 30 switch or indicator on the shore set synchronously with the switch on the torpedo and electrically connected with the main line and operated by the making and breaking of the circuit therein, substantially as described.
8. In a torpedo of the class described, the combination of propeller mechanism, rudder mechanism, an electric motor connected with the propeller mechanism arranged to run in one direction without regard to the direction of the current-supply, a motor connected with the rudder mechanism arranged to be reversed with the direction of current-supply, a step-by-step switch electrically connecting such motors together in series and connected with the propeller alone, electromagnetic mechanisms for operating the step-by-step switch, a single line-wire connecting the electromagnetic mechanisms and step-by-step switch with the shore, a key or similar element for making and breaking the main line, and a reversing-switch in such main line intermediate the source of current-supply and the step-by-step switch to change the direction of the current, substantially as described.
9. In a torpedo of the class described, the combination of propeller mechanism, rudder mechanism, an electric motor connected with the propeller mechanism arranged to run in one direction without regard to the direction of the current-supply, a motor connected with the rudder mechanism arranged to be reversed with the direction of current-supply, a step-by-step switch electrically connecting such motors together in series and connected with the propeller-motor alone, electromagnetic mechanisms for operating the step-by-step switch, a single line-wire connecting the electromagnetic mechanisms and step-by-step switch with the shore, a key or similar element for making and breaking the main line, a reversing-switch in such main line intermediate the source of current-supply and the step-by-step switch to change the direction of the current, a dummy indicating-switch on the shore, and electromagnetic mechanisms for operating the same connected with the main line and arranged to be operated as the circuit is made or broken therein, substantially as described.
10. In a torpedo of the class described, the combination of a propeller mechanism, rudder mechanism, an electric motor connected with the propeller mechanism arranged to run constantly in one direction and without regard to the direction of current-supply, a second motor connected with the rudder mechanism arranged to be rotated and reversed as the direction of current-supply is changed, a step-by-step switch provided with two concentric sets of conducting-segments—one set of such segments electrically connected with and connecting both of such motors in series and the other set of segments electrically connected with the propelling-motor alone, a switch-lever arranged to pass over such segments and be alternately and electrically connected with a conducting-segment first in one set and then in the other, electromagnetic mechanisms for rotating such switch-lever in a step-by-step manner, a single line-wire connecting such

electromagnets and the step-by-step switch-lever with the shore and with a source of current-supply, a key for making and breaking the circuit in such line and energizing and de-
5 energizing the electromagnetic mechanism to operate the same, and a reversing-switch in such main line intermediate the electromagnetic mechanisms and the source of current-supply to change the direction of the current, substantially as described.

11. In a torpedo of the class described, the combination of propeller mechanism, rudder mechanism, an electric motor connected with the propeller mechanism arranged to run con-
5 stantly in one direction and without regard to the direction of current-supply, a second motor connected with the rudder mechanism arranged to be rotated and reversed as the direction of current-supply is changed, a step-
by-step switch provided with two concentric sets of conducting-segments—one set of such segments electrically connected with and connecting both of such motors in series and the other set of segments electrically connected with the propelling-motor alone, a switch-lever arranged to pass over such segments and be alternately and electrically connected with a conducting-segment first in one set and then in the other, electromagnetic mechanisms for rotating such switch-lever in a step-by-step manner, a single line-wire connecting such electromagnets and the step-by-step switch-lever with the shore and with a source of current-supply, a key for making and breaking the circuit in such line and energizing and deenergizing the electromagnetic mechanism to operate the same, a reversing-switch in such main line intermediate the electromagnetic mechanisms and the source of current-supply to change the direction of the current, a dummy indicating step-by-step switch, electromagnetic mechanisms for operating the same connected with the main line and arranged to be energized and deenergized by the making and breaking of the circuit therein, substantially as described.

12. In a torpedo of the class described, the combination of propelling mechanism, rudder

mechanism, an electric motor connected with the propelling mechanism arranged to rotate in one direction without regard to the direction of current-supply, a second electric motor connected with the rudder mechanism and arranged to have its rotation reversed as the direction of current is reversed, a step-
5 by-step switch provided with two concentric circles of switch-segments alternately opposed, the conducting-segments in one circle being arranged opposite the spaces formed between the segments in the other circle, means electrically connecting the conducting switch-segments in one circle with both of the electric motors, means electrically connecting the conducting switch-segments in the other circle with the propelling-motor alone, a rotatable switch-lever arranged to contact the conducting switch-segments in each circle alternately—first a conducting-segment in one circle and then a conducting-segment in the other circle—and be out of electric contact with the switch-segments in the opposed circle, ratchet-and-pawl mechanism for operating the switch-lever in a step-by-step manner, electromagnetic mechanisms for operating the pawl-and-ratchet mechanism, a single line of wire connecting the electromagnetic mechanisms and the step-by-step switch mechanism with the shore and a source of current-supply, a key for making and breaking the circuit in such single main line, a reversing-switch intermediate the source of current-supply and the electric motors for changing the direction of current in the main line, a dummy indicating switch provided with an indicating lever-arm arranged to be operated in a step-by-step manner, pawl-and-ratchet mechanism for operating the same, a second electromagnetic device for operating the pawl-and-ratchet mechanism of the dummy indicator-switch, and means electrically connecting the second electromagnetic device with the main line so that it may be operated as the circuit is made and broken therein, substantially as described.
